THERMOELECTRIC SAFETY DEVICE

Harold A. Mantz, Milwaukee, Wis., assignor to
Milwaukee Gas Specialty Company, Milwaukee,
Wis., a corporation of Wisconsin

Application June 4, 1936, Serial No. 83,487

6 Claims. (Cl. 158—117.1)

My invention relates to an improvement in thermoelectric safety devices and the like.

While the device with which I shall describe the present invention hereinafter in connection

5 with the drawings is a particular type of thermoelectric safety valve and switch combination, it is to be understood that the present invention is not limited to use with any particular device but may be employed with all similar devices
10 and elsewhere as suitable or desired.

For example, the present improvement may be used with the thermoelectric safety switch shown and described in the copending application of John H. Thornberry and Harold A. Mantz, Serial
15 No. 14,551, filed April 4, 1935, which has matured into Patent No. 2,132,057, issued October 4, 1938, as well as with other thermoelectric safety devices of similar character.

Thermoelectric safety devices which depend
20 upon a weak voltage thermoelectric current for maintaining the flow of fuel for example to the main burner, and which operate to shut off the flow of fuel to such burner upon extinction of the pilot flame, require resetting means for resetting
25 the device after the pilot flame has been extinguished. These resetting devices usually move the armature into contact with the pole faces of the electromagnet, and, simultaneously, the switch or other control device to position for setting up the supply of fuel to the main burner. If the switch or other control device is operated
30 to set up the supply of fuel to the main burner when the resetting device is operated and irrespective of whether the pilot burner is lighted,
35 fuel may pass to the main burner and escape and collect unburned. This unburned gas presents the danger of asphyxiation and possible explosion when a flame is applied to light the pilot burner.

40 The object of the present invention is to provide means which will permit resetting and holding the armature in contact with the pole faces of the electromagnet without setting up the supply of fuel to the burner, and, particularly, means
45 which will permit resetting and holding the armature in contact with the pole faces of the electromagnet without setting up the supply of fuel to the burner until the pilot flame has been relighted and a thermoelectric current set up to
50 hold the armature in contact with the pole faces of the electromagnet.

The resetting device has a resetting button provided with a closure cap, and the supply of fuel is not set up to the burner until the pilot flame has been relighted to set up a thermo-

electric current to hold the armature in contact with the pole faces of the electromagnet and the closure cap has been applied into position covering the resetting button.

5 The fuel supply conduit for the main burner is controlled by an electrically operated valve, and it is one of the more specific objects of the present invention to provide contacts independent of the closure cap for controlling the circuit for this valve, one of these contacts being pressed into engagement with the other contact by the closure cap when said cap is in position enclosing the resetting element.

Another more specific object is to provide a pair of contacts for controlling the circuit for the electrically controlled valve or other device, with spring means for disengaging one of said contacts from the other contact when the closure cap is removed, the closure cap pressing the disengageable contact into engagement with the 10 other contact yieldingly through said spring means when the cap is in position enclosing the resetting element.

Another object is to provide a pair of fuel supply conduits, a thermoelectric device controlling the supply of fuel through both said conduits, means for resetting the thermoelectric device, and means for preventing the supply of fuel through one of said conduits during the resetting operation.

Another object is to provide a control valve, a control circuit having a switch therein, a thermoelectric device for holding the valve open and the switch closed, means for resetting the thermoelectric device, and means operable to open the 35 control circuit during the resetting operation.

Further objects and advantages of the invention will be apparent from the following detailed description, taken in connection with the accompanying drawings, in which:

40 Figure 1 is a fragmentary and more or less diagrammatic view showing an embodiment of the present invention in a pilot burner and main burner gas supply system;

Figure 2 is a top plan view of a thermoelectric safety valve and switch embodying the present invention;

Figure 3 is a vertical section on an enlarged scale taken on the line 3—3 of Figure 2; and

Figure 4 is an elevational view, partially in section, looking from the right hand side in Figure 3.

Referring to the drawings, the pipe 10, which may be the gas supply pipe for the main burner (not shown), is provided with an electrically op-

erated valve 12 of a type well known in the art.

The heater, appliance, or the like, is diagrammatically indicated at 14, and the main burner, which may be associated therewith in any suitable or preferred manner, may be controlled by the valve 12. This valve has electrically controlled mechanism connected into an electric circuit 15 which may be provided with a thermostat 16 to be opened or closed in accordance with the temperature of the room heated by the heater, where the heater is a room heater, or the thermostat 16 may be arranged to be opened and closed in accordance with the temperature of the water in the tank, where the heater is a water heater, or otherwise as desired. The circuit 15 may include the secondary winding of a transformer 17, which may be connected to a suitable source of current.

Associated with the main burner in the usual or in any suitable or preferred manner, is a pilot burner 18 which is intended to remain lighted and which may be of any suitable construction. This pilot burner 18 is supplied with fluid fuel by a tube 19 connected to the pipe 10 ahead of the valve 12.

The thermoelectric safety valve and switch is indicated in its entirety at 20 and is shown interposed in the fuel supply tube 19 for the pilot burner 18. It comprises an intermediate valve housing 30, a lower switch casing 31, and an upper electromagnet enclosing hood 32. These parts are held together by screws 33 which pass through openings in the bottom flange of the hood 32, down through openings in the housing 30, and have threaded engagement at their lower ends in threaded openings in the housing 31.

The intermediate valve casing 30 is hollow and has a partition wall dividing the interior thereof into an inlet chamber and an outlet chamber. The tapped inlet opening to the inlet chamber is adapted to receive the gas inlet pipe, and the tapped outlet opening from the outlet chamber is adapted to receive the gas outlet pipe which extends, for example, to the pilot burner. The valve casing 30 is thus interposed in the fuel supply tube 19. Formed in the partition wall is a valve opening 34 surrounded by a valve seat, against which a valve 35 is resiliently pressed by a compression spring 36 when the electromagnet, indicated at 37, is deenergized.

The electromagnet 37 is disposed within the hood 32 and comprises a U-shaped magnet frame 38 provided about each of its legs with a coil 39. The magnet frame is held rigidly to a magnet mounting plate 40 by means of a bracket which is secured to the plate by screws, as shown. The plate 40 is rigidly secured to the hood 32 by a screw 41. A name-plate may be provided as desired.

The magnet armature 45 is adapted to have engagement with the end portions of the U-shaped magnet 38. The armature is guided for reciprocatory movement within upright guide lugs on an armature guide 47 which is secured to the hood 32 by screws 48. One of said guide lugs is shown at 46 along the back of the armature 45, the other lug (not shown) being disposed along the front of the armature. The armature 45 has attached thereto, by upwardly extending bent-over portions, a cradle which is connected to the upper end of the valve stem 58, preferably in a manner to provide limited universal connection.

The valve disc 35 is secured to the lower end of the stem 58 by a cradle 52 which has an in-

turned upper end which cooperates with a U-shaped retainer 53 engaging in a groove in the lower end of the stem 58. A limited universal connection is thus provided between the valve member 35 and the lower end of the stem 58. The spring 36 is coiled about the stem 58 and confined between the flanged margin of the cradle 52 and a valve stem washer 55 which has packing 56 disposed above it and in a recess in the armature guide, so that gas cannot escape from the valve casing 30 into the hood 32. The under surface of the valve disc 35 has a gasket 58 clamped in a recess in the valve disc and between the disc and a washer by the resetting stem 60, the upper reduced end of which is threaded into the valve disc 35 as shown.

The resetting stem 60 extends downwardly through the valve opening 34 down, through an opening in the bottom of the valve casing 30, through switch casing 31, and out through an opening in the bottom of the switch casing. Packing is provided at 62 to seal the valve casing against gas leakage along the stem and into the switch casing. Fixed upon the lower end of the stem 60 is a resetting button 63 secured upon the stem by a retainer spring 64 and a screw 65. To prevent unwarranted actuation of the button 63, a closure cap 66 is threaded into the opening in the bottom of the switch casing and over the button 63 completely to enclose the button. This cap 66 is removed to reset the valve, and the switch is reset by resetting the valve and replacing the cap 66.

The stem 60 is slidable in an eyelet 68 which carries an insulating sleeve 69 and holds a washer 70 to the lower end of this sleeve. A ring 72 engages in a groove in the stem 60, and with the switch closed and the valve open, this ring is positioned above the upper end of the sleeve 69 a distance less than the spacing of the valve 35 above its seat. A contact disc 73 for bridging and connecting contact fingers 74 has a central opening provided with an eyelet with which a shoulder 75 on the sleeve 69 is adapted to cooperate in the downward movement of the sleeve 69 to disengage the bridging contact 73 from the contacts 74. The sleeve 69 is slidable in an insulating disc 76 which seats upon the upper end of the tubular extension of the cap 66 when this cap is in position enclosing the resetting button.

The contact fingers 74 have downturned ends (Figure 4) connected electrically to terminal bushings 78 and secured mechanically by said terminal bushings to an insulating terminal base 79 secured over a lateral opening in the switch casing 31. Spacers are provided at 80, and the tubular extensions of the bushings 78 are headed at 81 with a washer 82 interposed between the base 79 and each of these heads 81. Terminal screws 83 are threaded into each of the bushings 78, and these screws are provided with terminal washers 84. A terminal cover 85 is suitably secured by means of screws or the like (not shown) over the terminal screws 83 and the outer ends of the terminal bushings. The bottom of the cover 85 has openings provided with insulating grommets 86 through which the conductors, corresponding, for example, with the conductors 81 and 82 of Figure 1, are led into the terminal cover 85 and connected to the respective terminal screws.

A coiled spring 88 surrounds the insulating sleeve 69 and is interposed between the contact disc 73, and specifically between the eyelet 75 thereof and the insulating disc 76. This spring 75

holds the contact disc 73 yieldingly against the contact arm 74 when the device is in the position shown in Figure 3, and at the same time permits the armature 45 to be pressed and held firmly 5 against the ends of the legs of the magnet frame 38 without depending solely upon the yieldability of the contact arms 74. An insulating bushing 90, enlarged to surround the ring 72, is provided upon the stem 60, and a coiled spring 92 is interposed between a shoulder on this bushing and a washer pressed against the packing 62.

10 A thermocouple having a hot-welded junction 90 disposed in proximity to the pilot flame, shown more or less diagrammatically in Figure 1, is 15 connected at 93 to the thermoelectric safety device.

The operation of the device is as follows:

When the pilot flame 18 is burning, the heat 20 of the pilot flame upon the junction of the thermocouple produces a thermoelectric current in the coils 39. This thermoelectric current produces a magnetic field in the magnet frame and armature of sufficient strength so that when the armature is placed in contact with the ends of 25 the magnet frame by pushing the resetting button 63, the magnetic attraction holds the armature in raised position against the frame with a force greater than the force exerted by the spring means, thereby holding the contact disc 73 in 30 contact with the contact arm 74 and the valve 35 in open position so long as the pilot flame is burning.

If the pilot flame goes out, the thermoelectric current through the electromagnet 37 ceases, and 35 the springs 36 and 92 move the valve member 35 to closed position and, simultaneously, the contact disc 73 downwardly into open position out of engagement with the contact arms 74. The closing of the valve shuts off the supply of gas to 40 the pilot burner, and the opening of the switch opens the circuit for the safety control valve 12, whereupon this valve moves to closed position to close off the supply of gas to the main burner.

In the downward movement of the stem 60, 45 the ring 72 engages the upper end of the eyelet 68 or insulating sleeve 69, and moves the same downwardly. Upon this downward movement of the sleeve, the shoulder 75 thereof engages the eyelet 75' or the contact disc 73 and moves the 50 same downwardly into open position out of engagement with the contact arms 74 against the tension of the spring 88.

In resetting the device, the retainer ring 72 moves upwardly with the stem 60. The bridging 55 contact 73, however, is disengaged from the contacts 74 so long as the cap 66 is removed. When this cap is applied into position enclosing the resetting button 63, its upper end engages the insulating disc 76 and presses the contact 73 into 60 engagement with the contacts 74 yieldingly through the spring 88. A gasket 95 is preferably provided between the terminal base 79 and the switch casing 31, and gaskets are preferably provided at 96 and 97.

65 It is to be understood that the invention is not to be limited to the embodiment illustrated and described, but is capable of a wide variation of embodiments within the scope of the appended claims, and that changes may be made in the details of construction, arrangement, and relation of the parts.

Furthermore, while the invention has been illustrated and described as employed in conjunction with a pilot light, it will be apparent that 75 the invention may also be used as a safety de-

vice in connection with other devices as, for example, the thermocouple could be subject to the heat of a main burner where it is desired that the gas valve be closed whenever the main burner goes out. Furthermore, the valve casing of the present device may be connected into other gas lines than the pilot supply line as shown, and the switch may control other circuits than a circuit for a remotely disposed electrically operated valve in the gas line for the main burner. 10

I claim:

1. In combination, a control device comprising a valve housing, an upper housing secured to the top of said valve housing, a lower housing secured to the bottom of said valve housing, an 15 electromagnet in the upper housing, a thermocouple connected to said electromagnet for energizing said electromagnet, an armature adapted to be held to said electromagnet upon energization thereof, a valve disposed in the valve 20 housing and connected to said armature to be held in open position when said electromagnet is energized by said thermocouple, a switch disposed in the lower housing and connected to said armature to be held in closed position when said electromagnet is energized by said thermocouple, means for separating said armature from said electromagnet and opening said switch and closing the valve when said electromagnet is deenergized, means for resetting the armature against 25 said electromagnet, and means for opening said switch during the resetting operation.

2. In a device of the character described, an electromagnet, an armature adapted to be held in attracted position by said electromagnet when 35 said electromagnet is energized and movable to retracted position upon deenergization of said electromagnet, means for resetting said armature into attracted position, a closure cap for said resetting means, and a switch held closed 40 by said armature and said closure cap when the armature is in attracted position and said closure cap is in operative position, said switch being opened by movement of the armature to retracted position with the closure cap in place 45 and by removal of said closure cap from operative position with said armature in attracted position.

3. In a device of the character described, an electromagnet, an armature adapted to be held 50 in attracted position by said electromagnet when said electromagnet is energized and movable to retracted position upon deenergization of said electromagnet, means for resetting said armature into attracted position, a closure cap for 55 said resetting means, first contact means connected into an electric circuit, cooperating contact means, and yielding means biased between said cooperating contact means and said closure cap for holding said cooperating contact means in engagement with said first contact means when said armature is in attracted position and said closure cap in operative position and permitting separation of said cooperating contact means from said first contact means when said 60 armature moves to retracted position with said closure cap in operative position and upon removal of said closure cap from operative position with said armature in attracted position.

4. In a device of the character described, an 70 electromagnet, an armature adapted to be held in attracted position by said electromagnet when said electromagnet is energized and movable to retracted position upon deenergization of said electromagnet, a resetting stem for resetting said 75

armature to attracted position, a pair of contacts connected into an electric circuit and disposed on opposite sides of said resetting stem, a bridging contact engageable with said first contacts, a closure cap for said resetting stem, a stop member seating upon said closure cap when said cap is in operative position, and a spring biased between said bridging contact and said stop member for holding said bridging contact 10 yieldingly in bridging engagement with said first contacts when said armature is in attracted position and said closure cap in operative position and permitting separation of said bridging contact from said first contacts when said closure 15 cap is removed from operative position and when said armature is moved to retracted position.

5. In a device of the character described, an electromagnet, an armature adapted to be held in attracted position by said electromagnet when 20 said electromagnet is energized and movable to retracted position upon deenergization of said electromagnet, a resetting stem for resetting said armature to attracted position, a closure cap for said resetting stem, first contact means connected 25 into an electric circuit, cooperating contact means, a sleeve member on said stem, a stop member seating upon said closure cap when said cap is in operative position, a spring biased between said stop member and said cooperating contact means, abutment means on said stem and cooperable with said sleeve member to separate 30 said cooperating contact means from said first contact means by movement imparted to said stem upon movement of said armature to re-

tracted position, and abutment means cooperating with said stop member for moving said cooperating contact means into engagement with said first contact means in actuating said stem to reset said armature to attracted position. 5

6. In a device of the character described, a housing having a valve chamber, an electromagnet chamber and a switch chamber, an electromagnet in the electromagnet chamber, an armature adapted to be held in attracted position by 10 said electromagnet when said electromagnet is energized and movable to retracted position upon deenergization of said electromagnet, a dividing wall between said valve and switch chambers, a resetting stem for resetting said armature to 15 attracted position and having reciprocatory movement in said wall, a valve member mounted on said stem and operable in said valve chamber, a closure cap for said resetting stem, switch means disposed in said switch chamber and held 20 closed by said armature and said closure cap when the armature is in attracted position and said closure cap is in operative position, said switch means being opened by movement of the armature to retracted position with the closure 25 cap in place and by removal of said closure cap from operative position with said armature in attracted position, packing means sealing the passage of the resetting stem through the dividing wall between said valve and switch chambers, and yielding means biased between said 30 packing means and an element of said switch means.

HAROLD A. MANTZ.
